CLAIM

The ornamental design for an electrical charging station, as shown and described.

DESCRIPTION

FIG. 1 is a front perspective view of a first embodiment of an electrical charging station;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a front perspective of a second embodiment of the electrical charging station, wherein the solid black shading represents the color black; and,

FIG. 9 is a rear perspective thereof.

The broken lines in the drawings are for the purpose of illustrating portions of the electrical charging station that form no part of the claimed design. The symbols for the color silver in FIGS. 8 and 9 form no part of the claimed design.
